WINDOW SHADE ASSEMBLY

Lawrence S. Wilcoxon, Cincinnati, Ohio, assignor to Clopay Corporation, Cincinnati, Ohio, a corporation of Maryland

Filed Aug. 18, 1961, Ser. No. 132,353

3 Claims. (Cl. 160—326)

This invention relates to window shades and, more particularly, to a window shade of the type which utilizes a tubular roller, such as one made from steel.

A problem which has confronted manufacturers and retailers of window shades of this type for a long time has been that of providing window shades in the infinite number of lengths required in order to fit all windows. This problem is especially acute when a window shade is to be replaced, because in this situation the window shade mount brackets are already in place and their spacing determines the length of the window shade roller to be employed. Window shades utilizing wooden rollers are no particular problem, because they may be cut to size using an ordinary hand saw. Tubular steel is much more difficult, and it requires special tools and know-how in order to cut it neatly and accurately. Retailers of steel roller window shades have had to install special cutting tools, but the cutting has taken a considerable amount of time on the part of a specially trained clerk. This situation can be alleviated to some extent by the retailer keeping on hand a great number of different stock sizes; for example, stock sizes which vary by an inch from one to the other over the ordinary range of sizes sold. But, this practice also is objectionable, because it increases inventories unreasonably and unless the retailer has provisions for cutting, the in-between sizes require the resetting of the mounting brackets by the buyer or installer.

The primary objective of this invention has been to provide inexpensive means for varying the lengths of tubular rollers so that the number of stock sizes required for a complete retailer's inventory can be drastically reduced.

Toward this end there is provided an inexpensive expandable adaptor plug which receives the gudgeon pin of the window shade roller. In the preferred embodiment, this adaptor plug is molded of semi-resilient plastic material. It is adjustable axially within the tubular roller and it is easily expanded into locking engagement with the internal surface of the roller in any adjustable position. In my invention, this expansion is accomplished by utilizing the gudgeon pin as the expander. That is, the adaptor plug is fitted into the end of the tube to a point where the overall length is as required. Thereafter, the gudgeon pin is forced into a tapered bore within the plug which expands the plug to lock it securely in place within the tube.

The use of this plug fills in the gaps between the various lengths of tubes which may be carried in a reasonably sized inventory. Where it is desired to reduce the inventory of lengths to an even greater extent, the method of cutting disclosed here may be employed in conjunction with the adaptor plug; because, as will be seen, the adaptor plug takes the place of the usual end cap in which the gudgeon pin has been mounted in the past.

Hence, this arrangement of the elements accomplishes the objectives of reducing inventories, minimizing the number of elements necessary to provide an adjustable window shade assembly, reducing cost to a minimum, and it provides the purchaser with a simple means of length adjustment.

These and other objects will be readily apparent to one skilled in the art from the detailed description of the drawings in which:

FIGURE 1 is a front elevational view of the roller shade assembly.

2

FIGURE 2 is a front elevational view of the roller shade being cut to size.

FIGURE 3 is a front elevation of the roller shade being separated after having been cut to size.

FIGURE 4 is a transverse cross sectional view taken along the line 4—4 of FIGURE 1.

FIGURE 5 is a longitudinal cross sectional view of the adaptor plug.

FIGURE 6 is a front elevation of the gudgeon pin.

FIGURE 7 is an end view of a modified form of plug.

FIGURE 8 is a cross sectional view of the plug of FIGURE 7.

The roller shade assembly designated 1 comprises a tubular steel roller 2 having a shade 4 rolled thereon. This shade may be made of plastic, fabric or other appropriate materials. Mounted in one end of the tubular steel roller 2 is a conventional spring motor 6 such as that shown in Patent No. 2,586,340. Extending from the opposite end of the roller is an adaptor plug 8 from which extends one end 10 of a gudgeon pin 12.

Referring to FIGURES 2 and 3, it will be seen that a stock size window shade may be reduced in length by simultaneously cutting the window shade and tubular roller by means of a rotary steel disc cutter blade 14. The rotary steel disc cutter is passed through the shade 4 and on into the tubular roller 2 while the roller is rotated by mechanical means including a mandrel 16. After the cutter has heavily scored or cut through the tubular roller, the roller is shortened to size as shown in FIGURE 3. This cutting operation may take place in the retail store so that it is not necessary to supply an unlimited number of stock sizes to the retail store. After the window shade has been cut to size, the open end of the roller is closed by means of the adaptor plug 8.

The adaptor plug 8 is preferably made of a polyethylene material of one piece construction. The plug comprises a circular end portion or wall 18 from the periphery of which extends a cylindrical barrel 20 having an inwardly tapered end 22. On the periphery of the flange are two shoulders 24 and 26 which serve to locate the plug within the steel roller as will be fully explained herein. On the outside face of the radially extending portion 18 are two circular, concentric rings 32 which serve as bearing surfaces. Extending inwardly from the radially extending portion of the adaptor plug is an inwardly tapered hub portion 28. A tapered aperture 30 passes through the radially extending portion 18 of the adaptor plug and the inwardly tapered hub portion 28. Four equally spaced ribs 34 extend radially from the hub portion 28 to the interior surface of the cylindrical barrel 20. Located on the periphery of the cylindrical barrel 20 at a point between two of the ribs 34 is a groove 36 which extends from the end of the flange to the first shoulder 24. As may be seen in FIGURE 4, when the adaptor plug is inserted, the groove 36 fits over the lock seam 55 of the tubular steel roller, thus keying the plug in place and preventing rotation.

A gudgeon pin 12 fits into the annular aperture 30 of the adaptor plug and serves to expand the adaptor plug into tight engagement with the internal surface of the tubular steel roller. The gudgeon pin is cylindrical in shape and has a point 38 at one end. As shown, the outside diameter of the pin 12 is substantially equal to the outer end of the aperture or opening 30, but the opening tapers inwardly such that the inner end thereof is substantially smaller than the outside diameter of the pin. Adjacent the opposite end of the gudgeon pin is a radially extending flange 40 which abuts against the end of the adaptor plug and serves to locate the gudgeon pin therein. Due to the fact that the aperture 30 of the adaptor plug tapers inwardly, the hub 28, the ribs 34, and cylindrical barrel 20 will be expanded radially upon insertion

into the aperture 30 of the gudgeon pin 12. Thus, the adaptor plug may be inserted into the tubular roller up to the shoulder 24 and then expanded into engagement with the roller by means of the gudgeon pin 12. However, if the overall length of the assembly is just a little undersize, the plug can be pulled out and in this position expanded into engagement with the roller. On the other hand, if the assembly is oversize, the plug can be driven into the end of the steel tube by shearing off the shoulder 24 and in this position can be locked by the gudgeon pin 12. Thus a substantial latitude of adjustment for the overall length of the assembly is provided.

The modification of the plug illustrated in FIGURES 7 and 8 omits the cylindrical barrel 20 at the outer ends of the radial ribs 34. In this case, the outer surfaces of the ribs, indicated by the numeral 41, make contact with the inner surface of the tubular roller and when the plug is expanded by insertion of the gudgeon pin, the surfaces are tightly pressed into engagement with the roller, locking it in place. To assist in making the initial insertion of the plug, the outer ends of the ribs are tapered as shown at 42. The modified form of plug may be adjusted axially of the roller before the gudgeon pin is inserted to lock it in place, just as in the preferred embodiment.

It will be understood that the above detailed description is made by way of illustration and not limitation, it being contemplated that any modification in the details of the invention may be made without departing from the scope of the appended claims.

Having described my invention, I claim:

1. In a shade roller assembly having a tubular metal roller with a shade rolled thereon and a spring motor at one end thereof, the improvement to facilitate the adjustment of the overall length of the assembly comprising,

an expandible plug at the other end of said roller, said plug being an integral molding of semi-resilient plastic material having the characteristics of polyethylene, said plug having a circular end wall at the outer end thereof that is sufficiently larger in diameter than the inside diameter of said roller to prevent insertion of the plug into said roller beyond said end wall, an elongated cylindrical barrel portion extending from the inner face of said end wall, the axis of which is coextensive with the central axis of said circular end wall and which is of an outside diameter to be received in the roller in slip-fit relation when the plug is in unexpanded condition,

a hub portion extending from the inner face of said end wall the axis of which is concentric to the central axis of said end wall, said hub portion having an inwardly tapering central opening therein that opens through said end wall,

a cylindrical gudgeon pin having a pointed end receivable in the opening in said hub,

a plurality of radially disposed ribs interconnecting said barrel in said hub,

and the outer end of said opening in said hub being substantially equal in diameter to the diameter of said gudgeon pin but said opening tapering inwardly to a diameter substantially smaller than the diameter of said pin, whereby forceable insertion of the

pin into said opening expands said hub radially outwardly with the expanding force being transmitted to said barrel through said ribs to lock said plug within said roller.

5. In a shade roller assembly having a tubular metal roller with a shade rolled thereon and a spring motor at one end thereof, the improvement to facilitate the adjustment of the overall length of the assembly comprising, an expandible plug in the other end of said roller, said

10 plug being an integral molding of semi-resilient plastic material having the characteristics of polyethylene, said plug having a circular end wall at the outer end thereof that is sufficiently larger in diameter than the inside diameter of said roller to prevent insertion of the plug into said roller beyond said end wall,

the outer diameter of the remainder of said plug being of a diameter to be received in the roller in slip-fit relation when the plug is in unexpanded condition, an inwardly tapering hub portion extending from the inner face of said end wall the axis of which is concentric to the central axis of said end wall, said hub portion having an inwardly tapering central opening therein that opens through said end wall,

15 a cylindrical gudgeon pin having a pointed end receivable in the opening in said hub,

and the outer end of said opening in said hub being substantially equal in diameter to the diameter of said gudgeon pin but said opening tapering inwardly to a diameter substantially smaller than the diameter of said pin, whereby forceable insertion of the pin into said opening expands said plug radially outwardly to tightly engage the inner surface of said roll to lock said plug within said roller.

20 3. A plug and pin assembly for mounting in a hollow end of a shade roller comprising a plastic plug and a pin, said plug having an end wall, a plurality of radial vanes extending from said end wall and substantially normal thereto and an axially extending opening through said plug converging from said end wall along the inner edges of said vanes, and said pin having a shank of uniform cross-section and a pointed end, whereby insertion of said pin expands the vanes into gripping engagement with the hollow end of a shade roller.
